UNITED STATES PATENT OFFICE.

GEORGE R. MEYERCORD, OF CHICAGO, ILLINOIS.

COMPOSITE BOOTH, COUNTER, AND THE LIKE.

1,343,637.

Specification of Letters Patent. Patented June 15, 1920.

Application filed December 20, 1916. Serial No. 137,958.

To all whom it may concern:

Be it known that I, GEORGE R. MEYERCORD, a citizen of the United States, residing at Chicago, county of Cook, State of Illinois, have invented a certain new and useful Improvement in Composite Booths, Counters, and the like, and declare the following to be a full, clear, and exact description of the same, such as will enable others skilled in the art to which it pertains to make and use the same, reference being had to the accompanying drawings, which form a part of this specification.

The object of my invention is to produce a simple means for uniting and supporting slabs of vitreous or other material which will permit booths, inclosures, counters, slabs or partitions to be made at a comparatively low cost in forms which will be extremely attractive in appearance.

A further object of my invention is to produce a simple and novel means for supporting one end of the slabs or panels of vitreous or other material or of connecting two adjacent slabs or panels together whereby the stresses are distributed uniformly and are not concentrated as is the case where the attaching means are bolts or screws passing through the slabs or panels or clamps or brackets engaging the slabs or panels at points spaced apart from each other.

A further object of my invention is to produce a simple and novel means for uniting slabs of vitreous or other material which shall permit the use of metal posts or supports extending throughout the entire height of a wall, without the presence of projecting bolt heads or other fastening means.

A further object of my invention is to produce a means for uniting and supporting slabs of vitreous or other material which will permit a booth, counter or wall to be set up quickly and with the expenditure of a minimum of labor.

A further object of my invention is to produce a simple and novel arrangement by means of which a wall, booth or counter may be built up out of simple slabs and metal supporting tubes without the use of screws, bolts or other bolting devices.

The various features of novelty whereby my invention is characterized will herein after be pointed out with particularity in the claims; but, for a full understanding of

my invention and of its objects and advantages, reference may be had to the following detailed description taken in connection with the accompanying drawings, wherein:

Fig. 1 is a front view of a two compartment booth or toilet inclosure arranged in accordance with a preferred form of my invention;

Fig. 2 is a view looking toward the left at the right hand end of Fig. 1;

Fig. 3 is a section on an enlarged scale on line 3—3 of Fig. 2, the parts being broken away for the sake of clearness;

Fig. 4 is a horizontal section, on the same scale as Fig. 3, illustrating one complete compartment;

Fig. 5 is a front view of the lower member of one of the attaching channels for securing an end or partition wall to the building wall;

Fig. 6 is a front elevation of one of the upper sections of the attaching channel of which the device shown in Fig. 5 forms part;

Fig. 7 is a front view of a counter arranged in accordance with a preferred form of my invention, the top of the counter being omitted;

Fig. 8 is an end view of the counter;

Fig. 9 is a section on an enlarged scale taken approximately on line 9—9 of Fig. 7;

Fig. 10 is a section taken approximately on line 10—10 of Fig. 9;

Fig. 11 is a section taken approximately on line 11—11 of Fig. 7, the scale being the same as that of Figs. 9 and 10; and

Fig. 12 is a transverse section through a fragment of a wall and panel, illustrating a modified means for attaching a panel to a wall.

In accordance with my invention I employ channels for receiving the ends of each wall or panel in a wall; the mouths of the channels being narrower than the thickness of the slabs, and the slabs being suitably grooved on opposite sides in proximity to their ends so that the channels may be moved lengthwise into engagement with the slabs, with the lips of the channels entering the grooves. The channels may take any desired form. Thus, where they are used for attaching the rear ends of walls or partitions of toilet inclosures or booths to the wall of a building, the channels may be embedded in the plastering. On the front side of the inclosure or booth, at the cor-

ners of a counter, and at intervals along the front of a long counter, the channels may take the form of ornamental posts, being made, for example, of brass tubing. In assembling the wall, booth or counter, the channels are first set up and the slabs are then simply dropped in place; after which the channels may be filled with plaster or cement, making the joint extremely secure and at the same time giving solidity and rigidity to the posts.

In Figs. 1 to 6 I have illustrated a two-compartment booth or inclosure. Referring to these figures, 1, 1 represent two upright tubes into the lower ends of which are screw plugs, 2, having at their lower ends suitable supporting bases or feet, 3. Preferably only the upper ends of the plugs are screw threaded so that they take the form of simple cylinders for a considerable distance above the bases or feet. The purpose of this is to permit the plugs to be screwed in and out more or less to secure the desired vertical adjustment of the posts without exposing unsightly screw threads at the lower ends of the posts or standards. Each of the tubes is provided with a vertical slot, 4, extending from the extreme upper edge down to a predetermined point above the lower end of the tube. The end walls and partitions are made of slabs of vitrolite, marble, slate or other material each consisting preferably of two members, 5 and 6, lying back to back and secured together by a comparatively thick layer, 7, of cement which is preferably more or less resilient. Each slab is grooved in its two outer faces near the front edge as indicated at 8 so as to reduce the thickness of the slab at this point to the width of the slots in the tubular posts or standards. The slabs are simply slipped down into the upper ends of the slots, the lower edge of each panel made of a slab or a series of slabs resting at the bottom of one of the slots, so that the height of the lower edge of each wall or partition above the floor is determined by the location of the lower end of the corresponding slot. Each wall or partition may be built up of any desired number of individual slabs which need not all be of the same thickness; thus making it possible to produce various attractive effects, such as having thickened base or cap portions as indicated at 9 and 10. Neither need the length or width of each slab, measured from front to rear, be equal to the width of the wall or partition, but each panel or wall may be divided along vertical lines. When the various slab sections are assembled, small pins, 11, of any suitable size and shape may be thrust into the exposed surfaces of the cement of one section before the next section is laid in place, so that when the latter is pressed down, the pins enter the cement in the lower portion thereof and bind the two

overlying sections firmly together. This same expedient may be adopted in the vertical joints, as well as in the horizontal joints.

After all of the sections of the panel or wall have been placed in position, the interior of the tube may be and preferably is filled with plaster or cement as indicated at 12 and thereafter a cap, 13, is secured, preferably by screw threads, upon the upper end of the tube, insuring that the upper end of the tube will preserve its cylindrical shape and at the same time holding the sanitary panel firmly in place.

The rear end of each wall or partition is held to the building wall, 14, by channels which receive the adjacent ends of the slabs or panels in exactly the same way as the tubular posts. For the sake of convenience in assembling, and in order to make it unnecessary to carry in stock many different lengths of channels to suit walls of varying heights, I prefer to make the channels in sections; there being preferably a lowermost section, 15, having a slot, 16, similar to the slot 4, extending downwardly from the upper end of the member 15 and terminating at a distance from the lower end of the member 15 corresponding to the distance between the lower end of the slots 4 and the lower ends of the tubes 1. Additional sections, 17, each of which is preferably only a few inches long may be placed one on top of the other until the desired height of channel is reached. The members 15 and 17 may conveniently be made out of sheet metal suitably cut and bent, each section being preferably provided with perforated laterally projecting ears, 18, by which they may be fastened in place. The channels are placed in the wall, either before the wall is plastered or afterward, the plastering being cut away to permit the insertion of the channels if the latter are applied to a completed wall. The slab sections are grooved at their rear ends as at 8, in the same way as at the front ends, so as to provide reduced necks to be engaged by the lips of the channels.

The rear ends of the walls and partitions are rigidly held in place through their connection with the wall of the building and, while the lower ends of the front posts may be fixed to the floor in any suitable way, some means must be provided for holding the upper ends of the posts in proper spaced relation. This may conveniently be accomplished by connecting the several caps, 13, with the posts by cross pieces, 19, which are preferably in the form of tubing which, with the posts, forms a neat and simple frame at the front end of each compartment. If the last compartment of a row is placed adjacent to a side wall of the building as indicated at 20, the corresponding connecting piece, 19, may be provided with a flange, 21, adapted to be attached to this

wall. In this way an extremely rigid structure is obtained.

Doors, as indicated at 22, may be hung from the posts 1 which therefore serve also as door posts. Each door is provided with a plurality of hinges, one leaf, 23, of which is attached to the door while the other leaf takes the form of a casting, 24, adapted to extend around the supporting post as far as the vitreous slabs or panels will permit. The members 24 may therefore be slipped down upon the posts from the top and, after being positioned at the proper elevations above the floor, are preferably secured in place by bolts or rivets, 25, preferably the latter, each passing through the two arms of one of the hinge members and through the post embraced thereby. Each of the hinge members 24, except the last one in a row of booths or compartments, is preferably provided with a lug, 26, on the side opposite that at which the hinge joint is located, the lugs, 26, serving as door stops to limit the outward swinging movement of the doors of adjacent booths or compartments. With hinges and door stops of this type, the stresses upon operating the doors are transmitted to the posts and from them to the vitreous sanitary panels in such a way that there is no localization of stresses in the panels which will tend to injure or destroy them under rough usage.

In Figs. 7 to 10 I have illustrated my invention applied to a counter; the particular arrangement illustrated being one in which the front of the counter is made in two panels, 30 and 31, between which is placed a post, 32, which may in all respects be similar to one of the tubular posts 1 hereinafore described except that it is provided at diametrically opposed points with slots, 33, corresponding to the slots 4. The panels 30 and 31 are built up in the manner hereinafore described and their meeting ends are held together by the post 32 whose slots receive the reduced necks, 34, of the panels. At the front corners of the counter are posts, 35, 35, which are similar to the post 32 except that the slots 33 are arranged at right angles to each other so as to provide for the attachment of the adjacent end of each of the panels 30 and 31 with the corresponding end or side panel 36.

When it is desired to attach fixtures or brackets of any kind this may conveniently be accomplished by providing small castings, as indicated at 37 in Figs. 9 and 10, each casting having a hub, 38; the casting 37 being adapted to lie against the inner face of one of the tubular posts with the hub projecting outwardly through an opening in the post. A bracket, 39, or other suitable device may then be attached by means of a screw, 40, or the like, passing through the same and into the hub portion

of the casting. With this arrangement, any load on the member 39 is distributed over a considerable area of the supporting post, permitting the latter to be made out of a comparatively light tube. 70

The interior of the posts 32 and 35, as well as of the posts 41 supporting the rear ends of the side or end walls 36, may be filled with plastic material, 42, to make the posts solid. Rings, 43, slipped over the upper ends of the posts, and corresponding to the caps, 13, serve to hold the parts of the posts from spreading.

In Fig. 12 I have illustrated a modified form of channel for attaching one end of a slab or panel to a wall. In this arrangement the wall, 50, is simply grooved as at 51, to receive one edge of the slab or panel, 52. The usual grooves, 8, are provided in the slab or panel and into these grooves extend plates, 53, secured to the wall 50 at the sides of and overhanging the grooves 51. 85

While I have illustrated and described with particularity only a single preferred form of my invention with slight modifications, I do not desire to be limited to the exact structural details thus illustrated and described; but intend to cover all forms and arrangements which come within the 90 terms employed in the definitions of my invention constituting the appended claims. 95

I claim:

1. In combination, a tube having a slot extending lengthwise thereof from one end and terminating at some distance from the other end, a panel of vitreous material thicker than the width of said slot having one edge extending into the tube and a reduced neck lying in said slot, the space within the tube around said edge of the 100 panel being filled with plastic material, and a cap secured on the first-mentioned end of the tube.

2. A booth comprising a wall, separated channels secured in said wall and having contracted mouths directed outwardly, posts arranged in front of and parallel with said wall and having slots directed toward said channels, and a panel connecting each post and channel, each panel being thicker than 110 the width of the slot in the corresponding post and the width of the mouth of the corresponding channel and having reduced neck portions lying within said slot and said mouth, and a door arranged between said 115 posts.

3. A booth comprising a wall, separated channels secured in said wall and having contracted mouths directed outwardly, posts arranged in front of and parallel with said wall and having slots directed toward said channels, and a panel connecting each post and channel, each panel being thicker than 125 the width of the slot in the corresponding post and the width of the mouth of the cor- 130

responding channel and having reduced neck portions lying within said slot and said mouth, and a cross piece between said posts including caps fitting over the upper ends of the posts.

4. In a structure of the character described, a tubular post having on the rear side a slot extending lengthwise therein, a panel thicker than the width of the slot projecting into the post and having a reduced portion lying within the slot, a plurality of fittings extending around the post and having their ends terminating in proximity to opposite sides of said panel, fastening means extending through the arms of each fitting and diametrically through the post, a door, and a pivotal connection between the door and said fittings.
5. In a structure of the character described, a tubular post having a slot extending lengthwise thereof from one end and terminating at some distance from the other end, a panel of vitreous material thicker than the width of said slot having one edge extending into the tube and a reduced neck lying in said slot, and means for closing the open end of the slot and simultaneously clamping the tube upon the panel.

6. In a structure of the character de-

scribed, a tubular post having a slot extending through the same from the upper end and terminating at some distance from the lower end, a plurality of slabs of vitreous material thicker than the width of said slot lying one upon the other, one end of each of said slabs extending into the post and having a reduced neck lying in said slot, and means at the top of the post for closing the upper end of the slot and clamping the post against said slabs.

7. A booth comprising a wall, separated channels in said wall having contracted mouths directed outwardly, posts arranged in front of and parallel with said wall and having slots directed toward said channels, and a series of panels arranged edge to edge and connecting each post and the corresponding channel, each panel being thicker than the width of the slot in the corresponding post and the width of the mouth of the corresponding channel and having reduced neck portions lying within said slot and said mouth, and means for closing the upper ends of said slots to prevent displacement of the panels.

In testimony whereof, I sign this specification.

GEORGE R. MEYERCORD.
